UNITED STATES PATENT OFFICE.

JOHN M. HARTMAN, OF PHILADELPHIA, PENNSYLVANIA.

CINDER-CAR.

No. 815,162.

Specification of Letters Patent.

Patented March 13, 1906.

Application filed October 31, 1903. Serial No. 179,320.

To all whom it may concern:

Be it known that I, JOHN M. HARTMAN, a citizen of the United States, residing at 227 Gowen avenue, in the city of Philadelphia, county of Philadelphia, and State of Pennsylvania, have invented certain new and useful Improvements in Cinder-Cars, whereof the following is a specification, reference being had to the accompanying drawings.

10 My invention relates to that class of cars in which the discharge or dumping operation is effected by rocking the car-body, the preferred construction being one in which the bottom surface of the body itself is curved, 15 so as to roll upon the floor or upper surface of the truck-frame.

Among the objects of my invention are the following: To firmly seat the car-body in position during transit and to lock it in its normal position, to quickly and efficiently rock the body in either direction and insure the entire discharge of its contents at the desired point, to avoid the danger of tipping the body off from the frame by excessive movement, and to prevent injury to the actuating mechanism under the conditions of use.

Referring to the drawings, Figure I represents an end elevation of a car embodying all the features of improvement. Fig. II is a top or plan view thereof. Figs. III and IV are sectional views of some of the details, on an enlarged scale. Fig. V is a view, partly in end elevation and partly in transverse section, illustrating the position of the parts in the act of discharging.

The car-body is represented at 1 and is preferably constructed with the curved under surface indicated at 2, the axis of the curve being longitudinal with the truck, so as to rock toward either side.

3 indicates the truck, whose frame 4 has a floor or upper surface 6 of the configuration indicated in the cross-sectional views of Figs. IV and V. A shallow but wide recess 7 extends longitudinally along the central portion, forming longitudinal shoulders 9 9, and on each side of said shoulders, respectively, the floor inclines slightly downward outwardly to a line about over the treads 10 of the truck-wheels 11, from which region a more pronounced downward curvature is formed, as indicated at 13, the curved edges overhanging the wheels some distance, as shown. On its under side the frame 4 is provided with recessed bearings 15, in which are seated the coiled springs 16 17, resting upon

the axle-boxes 18 19. On the under side of the frame 4 downwardly-projecting lugs 21 22 are arranged in proper relation to subjacent bearing-points, such as the uppermost portions of the treads 10 of the several car-wheels 11, the relation, however, being such that when the frame 4 is in its normal or central position the lugs are supported clear of the bearing-points by the action of the 65 springs 16 17.

When the car-body is in its normal or central position, the rounded bottom surface 2 thereof rests upon the two longitudinal shoulders 9 9, as indicated at Fig. IV, so that a 70 relatively wide seat is afforded, which tends to prevent the accidental rocking of the car during transit. The car-body is provided with the usual chains 24 25 to insure parallelism in its rocking movement.

75 The actuating mechanism whereby the car is tilted or rocked comprises a pair of rocking arms 26 27, pivoted together at 29. The longer arm 26 is pivoted at its lower end to the frame, as indicated at 31. The upper 80 end of the arm 27 is pivoted at 32 to the car-body, the pivotal points 31 32 being vertically in line with each other and with the central axis of the body when in its normal position and at rest, as indicated in Fig. I. 85 The arm 26 is connected, by means of a link 34, with the piston of a cylinder 35, having the usual connections at 37 for the admission of fluid under pressure, such as steam from the locomotive-engine.

90 Referring to the position of the parts indicated in the end view of Fig. I, the piston is at the extreme right-hand end of the cylinder 35. If then the piston be moved to the left in said figure, it is obvious that the motion 95 communicated to the rocking arms 26 27 will rock the car-body to the left in Fig. I.

In Fig. I the initial position of the rocking arms is indicated as being at the right-hand side or toward the cylinder; but it is obvious 100 that they can be arranged in the reverse angular position on the opposite side of the axis of the car-body, the piston of the cylinder 35 being then at the extreme left-hand end of its stroke in said figure. In this case motion of 105 the piston toward the right-hand side of Fig. I would result in rocking the car-body toward the right of said figure. This extreme position is indicated in Fig. V, where it will be noted that by reason of the change of the 110 center of gravity of the structure as a whole the spring 16 has been relieved of pressure

and the spring 17 is compressed until the lug 22 rests upon the tread 10 of the car-wheel 11 on that side. It will also be noted that by reason of the overhanging downward curve 5 13 of the floor the car-body can be rocked into a position which insures the complete discharge of its contents at a region well clear of the track. The action of the spring 16 upon the side away from the discharge tends 10 to assist the rocking movement. Thus in Fig. V as the body is rocked away from the central axes the center of gravity changes until a point is reached where the relieved spring 16 exerts its force to further tilt the 15 floor in the right direction until the lug 22 brings up against its bearing-point on the tread of the wheel 11. In order to prevent accidental displacement of the car-body until the discharge is to be effected, I provide a 20 locking mechanism which may be used in either the position of the rocking arms. Upon each side of the center of the frame, at points which correspond with the alternative 25 positions of the rocking-arm 26, are mounted brackets 39 39, having sockets 40 40 adapted to receive the end of a screw-bolt 41, (shown in Fig. III,) engaging in a threaded cavity in the arm 26 and provided at its outer end with a hand-wheel 42. When the arm 26 is in its 30 normal position on either side of the central line, this bolt 41 can be screwed inward, so as to hold the arm 26 rigidly in position, the unlocking movement being of course effected by unscrewing the bolt, without, however, 35 wholly disengaging it from the arm 26.

In order to protect the working parts from careless handling of the draw-bar, I provide an outwardly-extended shield 45 in the form of a U-shaped band whose flanges 46 are secured 40 to the end of the car-frame. The draw-head 47 is mounted upon the outer end of said shield 45, which thus embraces the actuating devices in such a manner as to minimize the risk of the draw-bar striking or 45 punching them in the act of coupling.

It is obvious that various modifications may be made in the details of construction of my invention without departing from its essential features, and therefore I do not desire to limit myself to the precise construction and arrangement herein set forth.

Having thus described my invention, I claim—

1. The combination with the car-frame and the car-body arranged to rock thereon; of a pair of rocking arms pivotally secured to one another and to the frame and body; and, actuating mechanism for said arms connected to one of them between its connection with 55 the other arm and its connection with the car-frame, substantially as set forth.

2. The combination with the car-frame and the car-body arranged to rock thereon; of a pair of rocking arms pivotally secured to one another and to the frame and body; actuating mechanism for said arms connected to one of them between its connection with the other arm and its connection with the car-frame; and, mechanism for locking one of said arms in a position corresponding with 65 the normal position of the car-body, substantially as set forth.

3. The combination, with the car-frame and the car-body, adapted to rock thereon, of a pair of rocking arms pivotally secured to 70 one another and to the frame and body; a screw locking-pin mounted in one of said arms; and sockets for said pin, arranged on each side of the central axis in correspondence with the alternative positions of the 75 rocking arms, when the car-body is in its normal position, substantially as set forth.

4. The combination, with the car-body having a rolling under surface; of a truck-frame provided with supporting-wheels; 80 shoulders on said truck-frame extending transversely with respect to the axes of said wheels, adapted to form bearing-surfaces for the rounded portion of the car-body when the latter is in its normal position, substantially 85 as set forth.

5. The combination, with the car-body having a rounded under surface; of a frame having lugs on its under side arranged in correspondence with subjacent bearing-points; 90 and springs whereby the frame is normally retained in a position to clear said lugs from said bearing-points, substantially as described.

6. The combination, with the car-body 95 and its actuating mechanism comprising a lever-arm arranged to rock in a vertical plane; of an outwardly-projecting shield embracing said lever-arm; and a draw-head mounted upon said shield, substantially as described. 100

7. The combination with the car-frame and the car-body arranged to rock thereon; of a pair of arms arranged to rock in vertical planes; horizontally-disposed pivots securing 105 said arms to one another and to the frame and body; and, actuating mechanism for said arms comprising a stationary cylinder and a piston arranged to reciprocate therein in connection with one of said arms, substantially as set forth.

In testimony whereof I have hereunto signed my name, at Philadelphia, Pennsylvania, this 30th day of October, 1903.

JOHN M. HARTMAN.
